UNITED STATES PATENT OFFICE.

JOHN C. CROUT, OF PELION, SOUTH CAROLINA.

WINDOW-SCREEN.

1,175,130.

Specification of Letters Patent. Patented Mar. 14, 1916.

Application filed June 30, 1915. Serial No. 37,305.

To all whom it may concern:

Be it known that I, JOHN C. CROUT, a citizen of the United States, residing at Pelion, in the county of Lexington and State of South Carolina, have invented certain new and useful Improvements in Window-Screens, of which the following is a specification, reference being had to the accompanying drawings.

This invention relates to an improved window screen and has for its primary object to provide means for enabling the screen to be easily and quickly fitted in the window frame and firmly secured in position beneath the sash.

It is another object of the invention to provide a very simple and effective device of the above character, whereby the necessity of constructing the screen in relatively sliding sections is avoided and means provided in lieu thereof for readily effecting a tight and binding engagement of the screen with the window frame.

It is a further object of the invention to provide an improved window screen wherein the use of springs or analogous elements which soon lose their effectiveness, is avoided, and clamping means for the screen provided which may be applied to screens of the ordinary form now manufactured without necessitating any radical changes in the screen construction.

With the above and other objects in view, my invention consists in the novel features of construction, combination and arrangement of parts to be hereinafter more fully described, claimed and illustrated in the accompanying drawing, in which,

Figure 1 is a side elevation showing one of my improved screens mounted in the window beneath the sash; Fig. 2 is a section taken on the line 2—2 of Fig. 1; and Fig. 3 is a fragmentary elevation looking at the reverse side of the screen from that shown in Fig. 1 and illustrating the clamping bar in its released position.

Referring in detail to the drawing, 5 designates the screen frame which may be of any usual or ornamental construction and consists of marginal wood strips, indicated at 6, between which the wire screen fabric 7 is securely held. One of the vertical stiles of the screen frame is longitudinally channeled or recessed, as shown at 8. A bar 9 is also rabbeted or recessed, as at 10, to receive the reduced edge of the side bar or

stile of the screen frame. Spaced links 11 are pivoted at one of their ends, as at 12, upon one side of the screen frame and are pivotally connected at their opposite ends 60 by pins or screws 13 to the bar 9. Upon the opposite side of the screen frame a lever 14 is fulcrumed intermediate of its ends on the screw 15. The outer end of this lever is pivotally connected by a pin or screw 16 to 65 the bar 10, and by means of this lever said bar is adapted to be shifted with respect to the screen frame.

In the use of the invention, the lower window sash is raised and the screen fitted 70 into the frame beneath said sash, the lever 14 being on the inner side of the screen. When the screen is placed in position, the bar 9 is disposed with relation to the screen frame in the position shown in Fig. 3. The 75 operator now moves the lever 14 so that said bar is projected downwardly and laterally and into binding engagement with one side of the window frame. The screen is thus forced laterally and its opposite vertical 80 edge engaged against the other side of the frame. When the lever is in approximately horizontal position, as shown in Fig. 1, the ends of the movable bar 9 will be disposed in the same plane with the upper and lower 85 edges of the screen frame. The window sash is now lowered until the same engages upon the upper edge of the screen. In this manner, it will be seen that the screen may be very easily and quickly, as well as se- 90 curely arranged in position beneath the window sash or removed when it is desired to close the window. The screens may, of course, be constructed in various sizes and the movable bar 9 may be of any desired 95 width and moved to a greater or less extent by means of the lever so that the screen can be fitted into windows of various widths within certain limits.

From the foregoing description, the construction and several advantages of my invention will be fully and clearly understood. The use of the device requires no material alterations or changes in the ordinary screen construction and the additional cost entailed thereby is relatively small. The device is also very durable in actual use owing to the fact that no springs or other elements which might easily get out of order, are employed.

While I have shown and described the 110 preferred construction and arrangement of the several parts of the device, it is to be

understood that the same is susceptible of considerable modification and I, therefore, reserve the privilege of resorting to all such legitimate changes as may be fairly embodied within the spirit and scope of the invention as claimed.

Having thus fully described my invention, what I desire to claim and secure by Letters Patent is:—

10. In a window screen, a screen frame, a vertical clamping bar, said bar and one of the vertical side bars of the frame being rabbeted for interfitting engagement, spaced links pivotally connected at their ends to
15. the outer sides of said bar and the frame respectively, and an operating lever fulcrumed intermediate of its ends upon the

inner side of the screen frame and pivotally connected at one end to the clamping bar on the corresponding side thereof and midway between the ends of the latter whereby the clamping bar may be shifted laterally with respect to the screen frame and engaged with the window casing, said lever and the links at all times maintaining positions in parallel relation with respect to each other.

In testimony whereof I hereunto affix my signature in the presence of two witnesses.

JOHN C. CROUT.
